DESIGN FOR A COMBINATION REFRIGERATOR AND FREEZER CASING

Arthur Schupp, New York, N. Y.

Application December 28, 1945, Serial No. 125,089

Term of patent 3½ years

(Cl. D67—3)

To all whom it may concern:

Be it known that I, Arthur Schupp, a citizen of the United States of America, residing at New York city, in the county and State of New York, have invented a new, original, and ornamental Design for a Combination Refrigerator and Freezer Casing, of which the following is a specification, reference being had to the accompanying drawing, forming part thereof.

Fig. 1 is a perspective view of a combination refrigerator and freezer casing, showing my new design; and

Fig. 2 is a top plan view thereof.

I claim:

The ornamental design for a combination refrigerator and freezer casing, substantially as shown.

ARTHUR SCHUPP.
